UNITED STATES PATENT OFFICE.

GEORGE E. GRAY, OF COMPTON, CALIFORNIA.

PROCESS OF MAKING LIQUID FUEL.

Application filed July 2, 1920. Serial No. 393,525.

To all whom it may concern:

Be it known that I, GEORGE E. GRAY, a citizen of the United States, residing at Compton, in the county of Los Angeles and 5 State of California, have invented new and useful Improvements in Processes of Making Liquid Fuel, of which the following is a specification.

This invention is a process of producing 10 liquid fuel and has for its object the provision of a light hydrocarbon fuel of such specific gravity and flashing point as to adapt the same for use as the fuel for an internal combustion engine without necessitating pre-heating of the fuel.

The invention will be readily understood 15 from the following description of the accompanying drawing in which is shown an apparatus for carrying out the improved process.

By my improved process kerosene or any other of the heavier hydrocarbons is united 20 with a chemical agent having affinity for the hydrocarbon, and the resulting mixture is subjected to a gaseous hydrocarbon, which 25 through its affinity for the chemical agent will cause the uniting of the heavy hydrocarbon with the gaseous hydrocarbon to produce a hydrocarbon suitable for use, when 30 carburetted in the usual manner now employed in connection with internal combustion engines, to form a combustible mixture for the engine.

As a specific illustration of an example 35 of the improved process, I may mix commercial kerosene with acetone which through its affinity for the kerosene will readily mix therewith. The resulting mixture is then impregnated with a gaseous hydrocarbon, 40 preferably, a hydrocarbon consisting for the main part of one of the gaseous hydrocarbons of the paraffin series such as methane. This gaseous hydrocarbon may be natural gas as now obtained. The affinity of the 45 acetone for this gaseous hydrocarbon will cause a mixture to be formed including the heavy liquid hydrocarbon and the light gaseous hydrocarbon. This resulting mixture will be found to form a fuel of a specific 50 gravity and flashing point which readily adapts the same for use as the fuel for an internal combustion engine or for other uses wherever such a fuel is desired.

In the drawing I have shown means for 55 carrying out the process as thus set forth including a receptacle 1 wherein the heavy

hydrocarbon mixed with the acetone is adapted to be impregnated with the natural gas. The receptacle may include a perforated cage 2 in which are positioned particles of inert material adapted to be coated with the heavy hydrocarbon so that the gaseous hydrocarbon passing between said particles will have a large surface of the heavy hydrocarbon exposed to said gas for 60 permitting of the ready mixture of the gas and liquid. As an instance of this arrangement balls 3 of metal, stone, coke or the like may be provided in cage 2, the shape of these balls being such as to provide free passageways between the same and 65 through which the gaseous hydrocarbon may pass.

The heavy liquid hydrocarbon mixed 70 with the acetone may be supplied through 75 a pipe 4 having a perforated header 5 above cage 2 so that the liquid mixture supplied to receptacle 1 will flow downwardly over the balls 3. A pipe 6 for supplying the gaseous hydrocarbon, preferably, extends 80 upwardly through the base of receptacle 1 with a baffle 7 arranged to prevent the liquid flowing through cage 2 from entering the pipe 6. A discharge pipe 8 is provided at the base of receptacle 1, said pipe being, 85 preferably, provided with a cut-off valve 9 actuated by a float 10 which is also adapted to actuate a cut-off valve 11 provided in pipe 6. The valves 9 and 11 are adapted 90 to be closed as float 10 falls and rises respectively.

A certain proportion of the product 95 formed by the mixture of the liquid and gaseous hydrocarbons will be in a liquid form which will collect in the bottom of receptacle 1 and the remaining portion of the product thus formed will be in a gaseous state. This gas may be withdrawn from receptacle 1 through a conduit 12 communicating with the upper end of the receptacle 100 and leading to a condenser 13, preferably, provided with a perforated plate 14 supporting inert material such as previously described. Expansion of the gas within condenser 13 will cause liquefaction thereof, 105 said liquid collecting at the bottom of the condenser. A stand pipe 16, preferably, extends upwardly within the condenser below partitions 14, said stand pipe having a baffle 17 over the end thereof for preventing the 110 flow of the liquefied gas into said pipe. The excess of natural gas supplied to the re-

ceptacle 1 and flowing outwardly therefrom through pipe 12 and through the condenser will be withdrawn through pipe 16 in any suitable manner and may be returned 5 to pipe 6 for subsequent use in connection with the process or may be otherwise suitably employed.

A discharge pipe 18 is provided in the 10 base of the condenser, said discharge pipe being provided with a cut-off valve 19 actuated by a float 20 so arranged as to close the valve when the liquid level within the condenser drops. The liquid product formed by the improved process and collecting in 15 the bottom of receptacle 1 and condenser 13 may be piped to a suitable receiving tank through the discharge pipes 8 and 18.

In practice the proportion of acetone employed with the heavy hydrocarbon may be 20 .5% although obviously this proportion is subject to wide variations depending upon particular conditions as may be brought out during practical carrying out of the process. A sufficient amount of natural gas will be 25 supplied to thoroughly impregnate the heavy liquid mixture, the amount of said natural gas which is not mixed with the

heavy hydrocarbon to form the new combustible fuel, being recovered in an unchanged condition through pipe 16. 30

It will thus be seen that I have provided an improved process whereby a relatively light hydrocarbon may be formed from a heavy hydrocarbon by the mixture therewith of a light gaseous hydrocarbon in the presence of a uniting agent having an affinity for both the heavy and the light hydrocarbons. 35

While I have described a practical way of carrying out the improved process it will be 40 obvious that various changes may be made therein without departing from the spirit of the invention.

What is claimed is:

The method of producing a liquid fuel 45 consisting of mixing liquid hydrocarbon having the gravity of kerosene, or heavier than kerosene, with acetone, spraying the mixture over inert pieces to increase liquid surface in a chamber and introducing a gaseous hydrocarbon into the chamber. 50

In testimony whereof I have signed my name to this specification.

GEORGE E. GRAY.
